UNITED STATES PATENT OFFICE

HEINRICH KOPPERS, OF ESSEN-RUHR, GERMANY, ASSIGNOR TO THE KOPPERS DEVELOPMENT CORPORATION, OF PITTSBURGH, PENNSYLVANIA, A CORPORATION OF PENNSYLVANIA

ZINC-REDUCTION APPARATUS AND PROCESS

Application filed August 31, 1921, Serial No. 497,360, and in Germany January 8, 1917. Renewed October 19, 1927.

This invention relates to a large dimension oven for reducing zinc and similar volatile metals, and to a method of and for such reduction.

In the hitherto adopted, stepwise working, reducing ovens for zinc and similar volatile metals, the zinc ore, mixed with carbon, is normally reduced in small, closed vessels, the so-called zinc muffles, by outwardly heating these vessels; an oven of the customary construction in this connection holds from about 150 to 300 muffles. In heating the charge contained in the muffles, the oxidizing gases and vapors escape first, on which account this stage of the treatment takes place at a low temperature, so that zinc may not be reduced at once and taken away or oxidized with the diluting gases and vapors, thus getting lost. When the oxidizing gases and vapors have been expelled, the temperature of the oven is gradually raised to white heat. Now, it is a well-known difficulty to expel, in reduced form, the last particles of zinc which are still contained in the charge, and, as a general rule, this can only be accomplished with permanent white heat in the oven.

The building material hitherto used for these muffles, which is clay-bound and fire-proof, cannot stand these high temperatures very well, and there also form heavy scorifications between the residue of the distillation and the fire-proof building material. The idea of using lime-bound, fire-proof building material, so-called Dinas stones, which are distinguished by their fire-proof qualities and greater resistance to alkaline action, is opposed by the disturbing phenomenon that these stones easily become cracked and brittle with a change in the temperature. Thus in the literature on this subject, these Dinas or silica bricks have been rejected for zinc muffles used in stepwise operation because of the realization that on account of the cooling during the discharging and charging of the ovens the lime-bound building material is subject to premature deterioration.

The invention solves the problem of rendering a satisfactory use of lime-bound fire-proof bricks possible for zinc muffles operated stepwise, and rests, in this connection, on the

realization that this is possible when due care is taken to heat the distilling chamber quite uniformly on the one hand and constantly so high on the other hand that the heat withdrawal during the discharging and charging can only entail a very slight detrimental lowering of the temperature. Such a uniform and intense heating is allowable, however, if the zinc muffles are made as chambers after the fashion of the coke ovens, which are always enclosed between two heating walls divided into individual heating flues and provided with burners that can be regulated individually, and which are heated on the so-called regenerating principle, that is with heat recovery in the high-grade regenerators. The bond of the heating walls among themselves, which is created by the headers forming the individual heating flues, also makes it possible in this connection to safely hold in the best manner the inner pressures occurring in connection with the distillation of the charge.

So as to also be able to regulate the heating of the individual chambers according to the viewpoints mentioned, regenerators are suitably divided as in coke ovens, into regenerators forming a unit with the individual ovens, without the structural assembly of the chambers into an oven block being lost. The proposition of using large dimension ovens in place of the zinc muffles, has already been made, without the employment of the advantageous Dinas material on the one hand or constant and uniform heating on the other hand, or the characterized inner connection being utilized.

The lime-bound fireproof bricks already have the advantage that they resist basic action or influences, and thus scorification, better, and this advantage can be still further utilized by keeping the charge, by means of an insulating layer made of unmixed carbon, away from direct contact with the wall. In the reduction of metals, so as to make it possible conveniently to remove the molten metal cake from the crucibles, the proposition has also been made of lining this reducing vessel with an insulating layer. In the present case, however, other conditions enter into consider-

ation, and, furthermore, the manner in which this insulating layer is made in each case, according to the operation of the zinc distillation, plays an important part. From the zinc ore to be reduced and the carbon necessary therefore, the so-called cinder briquettes are made, for instance in the form of the well known egg briquettes, and these briquettes are supplied, at any one time, together with the proper quantity of loose unmixed cinder, to the distilling chamber, so that, by means of the natural embedding of the briquettes in the cinder the desired insulation is obtained. Even if some of the individual briquettes touch the wall, this contact, due to the egg-shape, only occurs on an infinitesimal surface, so that the danger of scorification is, to say the least, very greatly diminished. The same idea, however, can be still further perfected by using large rectangular briquettes made of zinc ore and cinder, and formed outside the oven structure into a cake of somewhat smaller dimensions than the inside measurements of the oven chambers; this cake is then introduced into the oven, similarly to the tamped cake in coking certain kinds of coal, while the space which remains between the cake and the oven wall is subsequently filled with cinder loosely introduced from above. In this manner there is obtained a complete enveloping of the charge proper with pure cinder; this produces the advantage at the same time that the heating gases that may leak through untight places in the walls, can only come in contact with the zinc ore in reduced form.

In the accompanying drawing a form of embodiment of the inventive idea is shown in which—

40 Figure 1 is a vertical section through a distilling chamber, on line I—I of Fig. 3.

Fig. 2 is a vertical section through a heating wall, on line II—II of Fig. 3.

45 Fig. 3 is a vertical cross section through chambers, heating walls and regenerators, all figures showing a reducing oven embodying the invention, the left hand part of Fig. 3 being on the plane of line III—III, and the right hand part of Fig. 3 being on the plane of line IV—IV, Fig. 2.

50 Referring to said drawings, the chamber *a* is charged from above through the charging-openings *b* with the aid of the charging car *c*, and is emptied after the reduction is accomplished, through the doorway in front of the chamber *a* after the door *e* on the front side of the chamber has been removed by means of the movable door handling device *d*. The choke damp developing during discharge through the doorway is carried away through a chimney *f*, while the ashes drop into a receptacle *g* lined in a fireproof manner, from which they can be discharged, as may be required, by lifting the slide *h*, into the receptacles *i*. Through the ports *k* of the

70 rear wall of the chamber the gases vaporizable at low and high temperatures that were developed in the chambers *a* enter the narrow channel *l*, in which a low temperature is maintained by means of cooling chambers *m* arranged on both sides (Fig. 3); within the channels *l* the condensation of the zinc vapors then takes place, so that liquid zinc can be discharged from the oven structure by means of the chute *n* and the uncondensed fractions vaporizable at lower temperatures can be discharged by means of the stack off-take *n'*. An important part as regards the satisfactory condensation of the zinc is played by the flowing downward from above of the zinc vapors, because this creates the most advantageous conditions for the requisite difference in temperature.

75 The chamber *a* is built up, similarly to a coke oven chamber, of fireproof molded bricks and enclosed between two heating walls *o* each, which themselves are again divided into and constituted of individual flame heating flues *p*; (Fig. 2); each of the flame flues is provided with one feed *q* for air and one feed *r* for gas (Fig. 3) and the flues can be further regulated for flow at their upper termination into the collecting channel *s* by means of slides *t*. In this manner an entirely uniform heating of the walls is rendered possible, a regulating manipulation being feasible at any point. Below the chambers *a* and the heating walls *o*, the regenerators *u* and *v* are arranged which are provided with a connection for communication with the waste heat channels *w* and the gas conduits *x*, or a connection with the outside air, in alternation. The operation of these regenerators is as customary in that all the chambers of one side are pre-heated by absorption of waste heat of exhaust gases from one half of the heating flues, while the heated fuels, gas and air, pass through the other regenerator chambers to be pre-heated by absorption of heat from the regenerators; after half an hour's time a reversal takes place in the direction of the draft, which results in the regenerators alternating in their tasks of absorbing and imparting heat from and to gas. On account of the fact that each chamber has its own regenerator, it is possible to influence each chamber as a whole in regard to the heating, notwithstanding the structural unity of a series of such chambers. The assembling of the individual chambers into one building block or battery, as is well known, not only commends itself for structural reasons, such as a saving in space, but also with reference to the diminished losses caused by heat radiation and the like.

80 85 90 95 100 105 110 115 120 125 130 In operating the oven structure for reducing zinc and similar volatile metals, the chambers *a* are constantly maintained at a high temperature sufficient to latilize concurrently both lower and higher boiling point fractions of charges within the respective

chambers *a*; the ports *k* discharge the lower and the higher boiling point volatilized fractions together and in gaseous form from the respective chambers and deliver them in gaseous admixture to the condensing channels *l*, wherein the gaseous admixture is subjected to the cooling effect of the cooling channels *m*; and the condensing channels *l* discharge the lower boiling point volatilized fractions, of the gaseous admixtures from the ports *k* of the respective chambers *a*, in gaseous form and the higher volatilized fractions thereof in liquid form.

What is claimed is:—

1. An oven structure for reducing zinc and similar volatile metals comprising, in combination: parallel distilling chambers arranged side-by-side; heating walls comprising individual and separately regulable vertical flame-flues between and contiguous to said chambers and regenerators connected with said flame-flues, for heating said chambers uniformly and for substantially constantly maintaining them at a high temperature sufficient to volatilize concurrently both low boiling point fractions and high boiling point fractions from material within said chambers; offtake means communicating with each of said distilling chambers for off-flow of low and of high boiling point fractions together and in gaseous admixture from the respective chambers; and condensing channels integral with said oven structure and communicating with the offtake means of the respective chambers for receiving said fractions in gaseous admixture therefrom, and adapted to discharge the lower boiling point fractions thereof in gaseous form and the higher boiling point fractions thereof in liquid form; whereby said distilling chambers may be uniformly heated to maintain them at substantially the same constant high temperature during the volatilization of both lower and higher boiling point fractions of charges therein.

2. An oven according to claim 1, characterized by the regenerators which form a uniform whole with the oven plant, being divided as described, into individual groups, so that each chamber, regardless of its structural connection with the others, can be operated and regulated as an independent unit.

3. An oven according to claim 1, characterized by the condensing channels respectively comprising a narrow space provided at the rear side of one of the oven chambers and regenerators, and cooled by surrounding cooling channels, the zinc vapors entering this space being liquefied into metallic zinc therein while falling downward from above.

4. An oven for the reduction of zinc ore, constructed with distilling chambers built side by side with intervening heating chambers and walls, and regenerators in pairs connected with said heating chambers, each set

of regenerators communicating with only one heating chamber, and condensing chambers for the zinc vapors connected with said distilling chambers.

5. An oven for the reduction of zinc ore, 70 consisting of a unitary built-up structure containing distilling chambers arranged side by side with intervening heating chambers and walls, and regenerators connected with said heating chambers and having air and gas supplying means, and condensing chambers for the zinc vapors connected with said distilling chambers.

6. An oven for the reduction of zinc ore, 80 consisting of a unitary structure containing distilling chambers arranged side by side with intervening heating chambers and walls, and regenerators connected with said heating chambers and having air and gas supplying means, and narrow channels for the zinc vapors and cooling channels alternating with said narrow channels.
